UNITED STATES PATENT OFFICE

HEINRICH HEETKAMP, OF DUISBURG, GERMANY, ASSIGNOR TO DEMAG AKTIENGESELLSCHAFT, OF DUISBURG, GERMANY

ROLLING MILL FOR WIDENING OUT TUBES

Application filed May 27, 1931, Serial No. 540,428, and in Germany June 11, 1930.

It is known in connection with the manufacture of seamless tubes to pass the partly made tube, immediately after it leaves the tube rolling mill, through a smoothing rolling mill, whereby the tube is not only smoothed but is restored to its circular shape. According to the present invention, a tube widening rolling mill in which the partially prepared tube is forced over a conical mandrel head with a rotary movement by means of inclined externally provided rollers and widened, is directly followed by a smoothing rolling mill comprising rods or plugs and externally provided operating rollers, this mill being in turn followed by a former bush for bringing the tube back to its circular shape, the former bush being provided to rotate more rapidly than the tube. The smoothing rolling mill is employed solely for smoothing the partially formed tube because the tubes, as they leave the widening rolling mill, are scratched by the edges of the widening rollers and the scratches must be removed. The tubes that have been smoothed by this method are continuously guided in a heated condition through the former bush, so that tubes ready for use are produced by the use, in co-operation, of the three apparatus hereinbefore described.

Apparatus according to the invention is diagrammatically illustrated in the accompanying drawing.

Figure 1 shows the apparatus in longitudinal section.

Figure 2 is a section of the apparatus taken on the line 2-2 of Figure 1.

Figure 3 is a section on the line 3-3 of Figure 1, and

Figures 4 and 5 are sections of the apparatus corresponding to Figure 2, to illustrate modifications of construction.

In the drawing, 1 is a mandrel, provided with the conical mandrel head 2. Within the head 2 are mounted conical rollers 3, which operate in conjunction with externally provided inclined mechanically driven rollers 4. The front head 5, which is connected to the head 2, serves to guide in the partially prepared tube 6. Beyond the rollers 3 and 4 a smoothing rolling mill is provided, disposed

in the direction indicated by the arrow α ; this smoothing rolling mill comprises externally provided, driven rollers 7 and a corresponding number of ribs 8 upon the mandrel 1. After the smoothing rolling mill a device is provided consisting of a rotatable funnel-shaped former ring 9; this is provided at the end of a bush 10 mounted so as to be rotated by means of the chain wheel 11.

The plant operates as follows:

The partially formed tube which is inserted between the rollers 4 and 5, is flared out at the end by the rollers until it becomes funnel shaped, and after the tube leaves these rollers it is in its flared out form forced over the ribs 8 with a rotary movement, where it is operated upon internally and externally by means of the externally provided smoothing rollers 7. This treatment causes the tube to lose its exact circular shape, and thus the tube, immediately after leaving the smoothing apparatus, is passed into the funnel-shaped rotating bush 10 and is restored to its circular shape. The forming action of the ring 9 upon the tube is considerably assisted, if the ring is rotated at a speed that exceeds the rotational speed of the tube as it moves past.

The apparatus is not limited to the construction illustrated. Thus the ribs or parts 8 may be replaced by rollers 11, as represented in Figure 4. Furthermore a rib 12 (Figure 5) in the form of a helix may be internally provided in such manner that the pitch of the rib changes continuously. The effect of providing this helical rib is to cause the tube to move forward, this being particularly necessary after the tube has left the flaring-out rollers 3 and 4. The alteration in the pitch of the thread formed by the rib prevents helical scratches in the tube from being exposed. The finished tube leaves the widening-out rolling mill at the end of the bush.

I claim:

1. A tube widening mill provided with a mandrel with conical head, externally disposed inclined rollers co-operating with said conical mandrel head, smoothing rolls behind said inclined rollers, means within the tube for its support against the smoothing

rolls, and a former bush following the smoothing rolls, which bush is rotated around the tube with a relative speed.

2. A tube widening mill according to claim 1, in which said means is provided with ribs disposed within the tube to co-operate with the smoothing rolls.
3. A tube widening mill according to claim 1, in which said means is provided with a helical rib within the tube to co-operate with the smoothing rolls.
